PNEUMATIC HORN

Norman F. Lewis, Wilkinsburg, Pa., assignor to
 The Westinghouse Air Brake Company, Wil-
 merding, Pa., a corporation of Pennsylvania

Application October 22, 1940, Serial No. 362,195

4 Claims. (Cl. 116—142)

This invention relates to horn devices of the type embodying a flexible diaphragm adapted to be vibrated at a rapid rate by variations in air pressure, to produce sound.

In devices of this type the flexible diaphragm is usually subject on one face to atmospheric pressure and has at the opposite face a pressure chamber, and either the diaphragm or a valve associated therewith is arranged to alternately open and close communication between said chamber and a passage through the horn bell leading to the atmosphere.

When the pressure chamber is at atmospheric pressure, the valve associated with the diaphragm is usually closed thereby, but when, due to operation of any suitable valve device under the control of an operator, the pressure chamber is connected to a source of fluid pressure which is of a degree different from that of the atmosphere, and a sufficient differential of fluid pressures is thereby created on the diaphragm, the diaphragm is operated to open said valve. The communication between the pressure chamber and source of fluid pressure is usually restricted with respect to the flow capacity of the communication connecting said chamber with the atmosphere through the horn bell so that when the latter is opened by the valve a sudden reduction in the differential of pressures on the diaphragm will occur to permit the diaphragm to close the valve. The differential of fluid pressures on the diaphragm is then again created and as a result the valve is again opened. This operation or vibration of the diaphragm continues as long as the pressure chamber is connected with the source of fluid pressure and is at such a rapid rate as to produce a sound suitable for signal purposes.

In horn devices of the above type the pressure chamber is normally at atmospheric pressure as above mentioned, and a certain period of time is therefore required to obtain a change in pressure in said chamber which is of sufficient degree to cause the diaphragm to operate. This delay is mostly due to the restriction in the communication between the pressure chamber and the source of fluid pressure, but may also be influenced by the tendency of the diaphragm to crack open the valve before a sufficient differential of pressures is obtained on the diaphragm to effect the full opening of the valve, and, as will be apparent, any such partial opening of the valve will delay obtaining said differential through the restriction above mentioned.

This delay or lag in operation of the horn device in response to an operator's connecting the pressure chamber with the source of fluid pressure is of a relatively small degree, but, nevertheless, is undesired particularly on railway locomotives employing devices of this type. The principal object of the invention is therefore to provide an improved horn device so constructed and arranged as to be more quickly responsive to operation of an operator's control valve or the like, than horn devices heretofore employed.

Other objects and advantages will be apparent from the following more detailed description of the invention.

In the accompanying drawing; Fig. 1 is a fragmentary cross-sectional view of a horn device embodying the invention; and Fig. 2 is a diagrammatic view of a control system embodying the horn device shown in Fig. 1.

The horn device shown in the drawing for illustrating one use of the invention, is preferably of the type usually employed on railway locomotives and which is adapted to be controlled by fluid at a pressure above atmospheric pressure from the usual supply carried on such locomotives.

In the drawing the reference numeral 1 indicates the body of the horn device which is provided with a suitable mounting bracket 2 and which has a passage 3 open at one end to a passage 4 provided in the small end of a horn bell 5 which is secured to the body 1. The opposite end of passage 3 terminates at an annular valve seat 7 provided in the body 1. A flexible laminated diaphragm unit 8 is disposed in body 1 in coaxial relation with the valve seat 7 and is clamped adjacent its peripheral edge between an annular shoulder 9 provided on a member 10 which is secured in the body 1 and an annular shoulder 11 which is formed on a cover plate 12 secured to body 1 by bolts 13. The plane including the shoulder 9 is offset from the end of the valve seat 7 and the shoulder 11 is of less diameter than the shoulder 9 so that when the cover 12 is secured in place, the diaphragm unit 8 will be placed under a desired stress and be deflected in the direction of valve seat 7.

The body 1 has an annular pressure chamber 14 formed around the valve seat 7 at one side of the diaphragm unit 8, and in this chamber is a valve 15 arranged to cooperate with said seat for controlling communication between said chamber and the passage 3. The valve 15 is mounted against one face of a spacer disk 16 the

opposite side of which engages one side of the diaphragm unit 8, and extending through said valve, disk, and unit is a rivet 17 which rigidly secures the parts together. The pressure chamber 14 is connected through a relatively restricted port 18 to a fluid pressure supply cavity 19 formed in the body 1. The cavity 19 is in turn connected to a pipe 20 leading to any suitable source of fluid under pressure such as a reservoir 28 and is thus adapted to be constantly supplied with fluid at substantially the pressure in said reservoir.

At the opposite side of the diaphragm unit 8 is a control chamber 22 which is connected by a passage 23 to a control pipe 24. The pipe 24 is adapted to be connected with a valve device 29 which will open said pipe to the atmosphere when it is desired to effect operation of the horn device. This valve device is adapted to normally close communication between the pipe 24 and atmosphere and may be of any desired type and arranged for control by an operator in any desired manner. In the horn device the passage 23 is connected to the fluid pressure supply cavity 19 through a passage 25 in which there is disposed a choke 26 having a restricted port 27.

In operation, let it be assumed that the reservoir 28 is charged with fluid under pressure, and that the valve device 29 is in its normal condition closing communication between the pipe 24 and atmosphere. Fluid under pressure from the reservoir 28 will then be supplied through the pipe 20 to cavity 19 in the horn device and from said cavity will equalize through the restricted port 18 into pressure chamber 14 and through the restricted port 27 in choke plug 26 into the control chamber 22 and pipe 24. With the pressure chamber 14 and control chamber 22 thus charged with fluid at the same pressures, such pressure in the chamber 14 acting on the back of valve 15 in conjunction with the force applied to said valve by deflection of the diaphragm unit 8 urges said valve into contact with the annular valve seat 7 to thereby close communication between the pressure chamber 14 and the outlet passage 3 leading to the horn bell 5. This is the condition which the parts of the horn device at all times will assume when not operating to produce a signal.

Now when it is desired to cause the horn device to operate to effect a signal, the operator actuates the valve device 29 to open the pipe 24 to the atmosphere through a communication having a flow capacity exceeding that of the restricted port 27 in choke 26. As a result, the pressure of fluid in control chamber 22 is suddenly reduced to substantially that of the atmosphere. Full reservoir pressure is at this time acting in the pressure chamber 14, and is thus promptly rendered effective to move or deflect the diaphragm unit 8 in the direction of the left-hand to unseat the valve 15.

When the valve 15 is unseated the vent communication from chamber 14 to the passage 3 leading to the horn bell 5 is opened and this communication has a flow capacity so exceeding that of the supply choke 18 that the pressure in said chamber is suddenly reduced into the horn bell to a sufficient degree for causing prompt reverse movement of the diaphragm unit 8 and consequent seating of the valve 15. When the valve 15 is thus reseated, the pressure of fluid in chamber 14 is again increased by the supply through the restricted port 18 to a degree sufficient for deflecting the diaphragm 8 in the

direction of the left-hand for again unseating the valve 15. The pressure of fluid in chamber 14 is then again suddenly reduced to allow reseating of the valve 15. This cycle of operation, or vibration of the diaphragm unit 8, occurs at a sufficiently rapid rate to cause vibrations of the air column in passage 3 and thereby in passage 4 of the horn bell, which will produce an audible sound suitable for signaling purposes, and will continue as long as the control chamber 22 is maintained open to the atmosphere through the operator's control valve device 29.

It will be noted that when the operator's control valve device 29 is venting the pipe 24 there will be a constant leak of fluid under pressure from cavity 19 through port 27 in choke 26 to said pipe, but such leakage is so restricted as to have no effect on operation of the horn device.

When the operator desires to terminate the signal, he allows the valve device 29 to close the vent from pipe 24 following which the supply of fluid under pressure through port 27 to passage 23 and thereby to pipe 24 and control chamber 22 in the horn device will increase the pressure in said chamber to equalization with that supplied to pressure chamber 14 and this permits the pressure of fluid in the pressure chamber 14 acting on the valve 15 to hold said valve in seating contact with the seat 7.

The venting of fluid under pressure from chamber 22 to effect operation of the horn device may be effected at as rapid a rate as desired due to the fact that the flow capacity through the passage 23, pipe 24, and the operator's valve device 29 need not be limited or restricted in any way since the operation of the horn device is entirely independent thereof. By this improved structure the pressure chamber 14 can always be normally charged with fluid at a pressure sufficient to cause the horn device to promptly operate upon the sudden venting of fluid from the chamber 22, it therefore being apparent that the restriction 18 between cavity 19 and pressure chamber 14 will in no way retard response of the horn device to operation of the operator's valve device 29, as occurs in structures in which the pressure chamber 14 as well as the chamber at the opposite side of the diaphragm are both normally at atmospheric pressure and in which fluid under pressure has to be supplied to the chamber 14 through the restricted opening 18 for causing the horn device to operate.

The invention is associated with a horn device of the type adapted to be operated by fluid at a pressure greater than atmospheric pressure, but it is equally applicable to horn devices adapted to be controlled by vacuum or pressure below that of the atmosphere, as will be readily apparent.

While only one embodiment of the invention has been shown and described in detail, it is not the intention to limit the scope to that embodiment or otherwise than by the terms of the appended claims.

Having now described my invention, what I claim as new and desire to secure by Letters Patent is:

1. A pneumatic horn device comprising a vibratory diaphragm structure having at one side a pressure chamber in constant communication with a source of fluid under pressure through a relatively restricted opening and controlling a communication of greater flow capacity than said opening between said chamber and atmosphere, said diaphragm structure being operative by the differential between the pressures in said

pressure chamber and atmospheric pressure acting on the opposite side of said diaphragm structure to open and close said communication for varying said differential to effect vibration of said diaphragm structure, and means controlling the pressure on said opposite side of said diaphragm structure and selectively operative to either subject said opposite side to atmospheric pressure for rendering said diaphragm structure operative or to a different pressure for holding said diaphragm structure in the position for closing said communication.

2. A pneumatic horn device comprising a vibratory diaphragm structure having at one side a control chamber adapted to communicate with the atmosphere and having at the opposite side a pressure chamber in constant communication with a source of fluid under pressure through a relatively restricted opening and controlling a communication of greater flow capacity than said opening between said pressure chamber and atmosphere, said diaphragm structure being operative by the differential between the pressures in said chambers when said control chamber is at atmospheric pressure to open and close said communication for varying said differential to effect vibration of said diaphragm structure, and means operative to either open said control chamber to the atmosphere to provide for vibration of said diaphragm structure or to provide for charging of said control chamber with fluid under pressure from said source for holding said diaphragm structure in the position for closing said communication.

3. A pneumatic horn device comprising a vibratory diaphragm structure having at one side a pressure chamber in constant communication with a source of fluid under pressure through a relatively restricted opening and controlling a communication of greater flow capacity than said opening between said chamber and atmosphere, said diaphragm structure having at the opposite side a control chamber, means connecting said control chamber to said source of fluid under pressure for balancing the pressures in

said pressure and control chambers to render said diaphragm structure operative to close said communication, and means for opening said control chamber to the atmosphere through a communication having a flow capacity such as to reduce the pressure in said control chamber substantially to that of the atmosphere, said diaphragm structure being operative by the differential between the pressures in said pressure chamber and substantial atmospheric pressure in said control chamber to open and close the communication controlled thereby for varying said differential to effect vibration of said diaphragm structure.

4. A pneumatic horn device comprising a body having a supply chamber constantly supplied with fluid under pressure, a vibratory diaphragm structure disposed in said body and having at one side a control chamber connected to and supplied with fluid under pressure from said supply chamber, said diaphragm structure having at the opposite side a pressure chamber in constant communication with said supply chamber through a relatively restricted opening, said diaphragm structure controlling a communication of greater flow capacity than said opening between said pressure chamber and atmosphere, means for venting fluid under pressure from said control chamber at a rate exceeding the rate of supply thereto to thereby subject said diaphragm structure to substantial atmospheric pressure in said control chamber, said diaphragm structure being operative when the pressure of fluid in said control chamber substantially equals that in said supply chamber to maintain the communication between said pressure chamber and the atmosphere closed and being operative by the differential of pressures in said control and pressure chambers when said control chamber is open to the atmosphere to alternately open and close the last named communication for varying said differential to effect vibration of said diaphragm structure.
